UNITED STATES PATENT OFFICE

CLARENCE E. REED, OF WICHITA, KANSAS, ASSIGNOR TO CHICAGO PNEUMATIC TOOL COMPANY, OF NEW YORK, N. Y., A CORPORATION OF NEW JERSEY

DEEP-WELL-DRILLING APPARATUS

Application filed September 22, 1927. Serial No. 221,271.

My invention relates to improvements in deep well drilling apparatus, and more particularly it relates to improvements in the structure of the bit head.

5 An object of the invention is to eliminate excessively rapid wear of the bit head due to the cutting thereof by sand in the flushing fluid.

10 A further object is to provide means for preventing loss of oil due to leakage.

The invention consists in the features, combination, and arrangement of parts hereinabove set forth and particularly brought out in the claims.

15 In the drawings:

Figure 1 is a vertical sectional view of the bit head.

Fig. 1^a is a plan view of the wash pipe plug.

Fig. 2 is a view partly in section taken on 20 line 2—2 of Fig. 1.

Fig. 3 is a view partly in section taken on line 3—3 of Fig. 2.

Fig. 4 is a view of a preferred modified form of oil screw shown in place in the bit 25 head.

Fig. 5 is a further modification.

Referring to the drawings, 1 represents the bit head having a central longitudinal bore 2 constituting a conduit for the flushing 30 fluid. The bore 2 has an enlargement 3 at its upper end screw threaded to receive wash pipe plug 4 having wrench sockets 4^a.

The bore 2 is of uniform diameter and circular cross-section from its juncture with enlarged bore 3 down to within a short distance 35 from its lower extremity at the crotch of the V-shaped recess 5. From point 6 to its extremity the bore 2 is flattened diametrically to nearly elliptical shape but with flat opposed sides 7, as shown in Fig. 2. At 6 shoulders are provided on the head within the bore 2 by reason of the flattening of the bore and the shoulders provide for limiting downward 40 movement of wash pipe 8 which is shaped externally to fit the bore 2, both as to the cylindrical portion and as to the flattened portion thereof.

Internally the wash pipe 8 tapers at 9 down to a bore 10 flattened similarly to the corresponding portion of bore 2.

The wash pipe 8 which is preferably of manganese steel eliminates the very marked tendency of the flushing fluid to cut the bore of the bit head, which tendency has been particularly noticeable at the extreme lower end of the bore, that is, in the crotch of the V-shaped recess in the head. The exterior flattening of the wash pipe 8 is to hold it against rotation within the bore. The interior flattening of the wash pipe 8 is to produce a flattened nozzle which will deliver a flattened jet to more effectively wash the cutters.

The shape of the sleeve or wash pipe 8 permits it to be cast of manganese steel, which is too hard to be machined.

The wash pipe is assembled in the bit head by dropping it into the bore 2 from the threaded shank end. The wash pipe plug 4 is then screwed tightly into place, jamming against the sleeve or wash pipe and holding it securely in position, the wash pipe bearing against shoulders 6. From this construction it will be apparent that the very hard manganese steel wash pipe will take all the scouring of the sand and eliminates such wear from the bit head.

It has also developed in field work that there is some leakage of oil about the shank 11 of the bearing, due to the extreme pressure 45 existent in the bottom of the deep wells with the differential of pressure within the stem. This leakage of oil about the shank interferes with its passage to the interior of the cone roller cutter and some of the oil is lost.

The present invention overcomes this difficulty by counterboring the end of the oil lead 12 in the bearing shank 11 and placing in this counterbore 13 a gasket or packing 14 made of rubber or hydraulic packing, slightly 50 projecting beyond the periphery of the shank. This packing or washer is bored with a hole 15 to align with the oil lead 12. The packing washer 14 which projects slightly beyond the peripheral surface of the shank is, upon insertion of the shank 11 in its bore 16, compressed tightly against the wall of the bore 55 and seals the passage against leakage about the shank.

In Fig. 2 a development of this idea is 100

shown wherein two screw plugs 17 and 18 are used to effect a tight joint to prevent leakage of oil about the shank. The bit head is provided with a lateral bore 19 of varying diameter extending from communication with the bore 16 of the bearing shank 11 outwardly and opening at the outer wall of the bit head at 20. The bore 19 is screw threaded at its largest diameter outer portion 21 and at its smallest diameter inner portion 22, but not at its intermediate portion 23 which is of intermediate diameter. The counterbore 13 in the shank 11 is filled with a rubber gasket 24 against which a hollow plug 18 bears, the plug having screw threaded connection with portion 22 of the bore 19. The plug 18 is provided with a rounded bearing edge 26 and a kerf 27 for screwing the plug by means of a driver inserted through bore 19. Back 20 of the gasket plug 18 is the intermediate bore portion 23 which is in communication with the oil passage 28 in the bit head. The hole is closed by a body plug 17 screwed into the outer bore portion 21. By this construction 25 the tension of the hollow gasket plug 18 will regulate the effectiveness of the seal against oil leakage.

Referring to Fig. 4, a very effective modification of the invention is shown in which 30 but one screw plug is used. The inner end of this plug 30 is a straight cylindrical body portion with an enlarged diameter about the middle portion and a still larger diameter at the threaded head of the plug. An annular 35 recess 31 is provided in the middle portion of the plug so that constant communication is assured with oil passage 32. Radial passages 33 connect recess 31 with bore 34 in the plug which communicates through washer 35 with oil lead 36 and central bore 37 of the shank to convey the oil to the cutters. The plug is provided with a wrench socket 38 and a copper gasket 39 is used to seal the contact at shoulder 40.

In Fig. 5 I show a further modification in which the shank of the roller cutter unit is provided with stepped shoulders 41 of different diameters facing upwardly, the larger diameter shoulder being lowermost, and in 50 the bore or recess of the head are complementary shoulders. These shoulders are so related that when the shank of the unit is seated in the recess there will be a space between the shoulder on the shank and the opposing shoulder in the recess or socket, and in this space gaskets 45 and 46 will be located to make an oil tight joint above and below the port or passage which conveys the oil from the duct in the head to the duct in 55 the shank.

The shank is provided at its upper end with means 42 by which it is held up in place. This means may be such as that shown in Letters Patent of the United States granted 65 to me July 19, 1927, No. 1,636,668, or No.

1,636,669 (Blauvelt assignor), by which the gaskets will be under sufficient compression to make a tight joint. As in the patents referred to, the roller cutter unit has a base portion 43 to contact with the inclined lower 70 surface of the head at the end of the bit head. This wall forms the abutment which resists the upward thrust to which the roller cutter unit is subjected. The shoulders are so related that when the base of the unit is seated against the lower end of the head the gasket will be under the desired compression to make an oil seal.

Roller cutters 44 are mounted on the lower part of the units as shown in Figs. 1 and 5. 80

I claim:

1. In combination with the bit head having a recess to receive the shank of a roller cutter unit, and provided with stepped shoulders within said recess, a roller cutter unit having a shank fitted to said recess with shoulders complementary to those of the recess, gaskets between said shoulders, an oil conduit extending across the joint between the shank and recess wall and between the gaskets, said unit having a base portion to seat against the lower end of the head, and means for holding the shank of the unit in the head, substantially as described. 90

2. In combination with a bit head having a recess to fixedly receive the shank of a roller cutter unit, a roller cutter unit having a shank removably and non-rotatably fixed in said recess, communicating oil conduits in the shank and head, and means for sealing the joint between the shank and the head adjacent the juncture of the oil conduits to prevent oil leakage through said joint, said conduits extending through the bodies of the shank and head from their fixed point of communication. 100

3. Apparatus according to claim 2 in which said sealing means comprises gaskets surrounding the shank and sealing the circumferential contact of the shank with the head above and below the juncture of the oil conduits. 110

4. Apparatus according to claim 2 in which said recess and shank are of general cylindrical shape and provided with complementary stepped shoulders above and below the juncture of the oil conduits, and said sealing means comprises gaskets surrounding the shank and disposed between said shoulders, and means for holding the shank of the unit in the head with the gaskets clamped between the complementary shoulders and preventing leakage of oil past said shoulders. 115

5. Apparatus according to claim 2 in which said recess and shank are of general cylindrical shape but having upper and lower cylindrical portions of relatively small and large diameter respectively, and an intermediate portion of intermediate diameter, the oil conduit in said head opening diamet- 125

130

rically of the intermediate portion of the recess, and the oil conduit in the shank opening diametrically of the intermediate portion thereof to communicate with the oil conduit in the head, said upper, lower and intermediate portions of the shank and recess providing complementary shoulders to receive the said sealing means.

6. Apparatus according to claim 2 in which
10. said recess and shank have upper and lower portions of relatively small and large cross-sectional area respectively, and an intermediate portion of intermediate cross-sectional area, the oil conduits in said shank and head
15. communicating at the said intermediate portions thereof, said upper, lower and intermediate portions of the shank and recess providing complementary shoulders above and below the oil passage to receive the sealing
20. means.

7. In combination with a head, a roller cutter unit having a shank removably and non-rotatably fixed therein, communicating oil conduits in the shank and head, means
25. for sealing the joint between the head and shank, adjacent said communicating oil conduits to prevent oil leakage through said joint, said conduits communicating in a direction transversely to the axis of said shank
30. and connecting with a longitudinal duct with which said shank is provided, substantially as described.

In testimony whereof I affix my signature.
CLARENCE E. REED.
